(57) **CLAIM**

The ornamental design for a universal back of chair hanger, substantially as shown and described.

DESCRIPTION

FIG. 1 is a front perspective view of a universal back of chair hanger in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof attached to a chair; and,

FIG. 9 is a back perspective view thereof attached to a chair. Any shading or hatching are not features of the design and are merely utilized to illustrate surface contours of the design in the drawings. The broken lines of FIGS. 8 and 9 are to illustrate environment only. None of the broken lines form a part of the claimed design.

1 Claim, 9 Drawing Sheets
